STOP MECHANISM FOR ROTATING ELEMENTS

George Zindel, Jr., Fox Chase Manor, Pa., assignor to Philco Corporation, Philadelphia, Pa., a corporation of Pennsylvania.

Application April 16, 1948; Serial No. 21,333.

5. Claims. (Cl. 74—10.7).

1.

This invention relates in general, to stop mechanisms and, more particularly, to stop mechanisms adapted for use with mechanisms including rotating elements.

Further and more specifically, as hereinafter described, the invention is concerned with automatic means for positively stopping the rotation of tuning mechanisms at preselected terminal positions.

The principal object of the invention is to provide means automatically operative to stop rotating elements positively at the completion of a predetermined number of revolutions.

Another, and more specific object of the invention is the provision, in cord-driven tuning mechanisms, of automatic means operative to stop rotation of the mechanism at preselected terminal positions, between which the mechanism is free to rotate in either direction.

A further object of the invention is the provision of such stop means characterized by its simplicity, its ruggedness, and its ease of operation.

These and other objects of the invention hereinafter appearing will be more readily understood by reference to the several views of the accompanying drawing, in which:

Figure 1 is a perspective view showing the apparatus of the invention associated with a pair of variable capacitors of the type commonly used for tuning radio apparatus;

Figure 2 is a fragmentary elevational view, partly in section, illustrating the invention in one phase of its operation;

Figure 3 is a view similar to Figure 2, but showing the apparatus in another phase of its operation;

Figure 4 is a fragmentary sectional view taken as indicated by line 4—4 of Figure 3;

Figure 5 is a view similar to Figure 4, but showing the parts in another position; and

Figure 6 is a fragmentary sectional view taken along line 6—6 of Figure 3, and showing the mechanism in another condition of operation, just prior to the condition shown in Figure 3.

Referring now with more particularity to the several figures of the drawing, illustrating the preferred embodiment of the invention, the numeral 10 designates, generally, the condenser assembly which is of well known construction including two stator sections 11 and 12, and corresponding rotor sections 13 and 14, respectively, each comprising a plurality of spaced plates. Rotors 13 and 14 are mounted upon a common shaft 15 journalled in end plates 16 and 17, and are

2.

adapted for rotation into and out of meshing relation with the stator sections, the spacing of the plates providing the necessary air-gap therebetween. A centrally positioned plate 18 separates and shields the condensers from each other.

Shaft 15 extends through plate 17 and has a pulley 20 attached to the end 19 thereof. Positioned immediately beneath pulley 20, and substantially at right angles to condenser shaft 15, is a drive shaft 21 journalled in walls 22 and 23 of a housing member 24. The latter is attached, as by screws 25—only one of which is shown—to plate 17 of the condenser assembly.

Drive shaft 21 is provided with a longitudinal slot 26 extending along the axis of said shaft (Figure 2), and within which a key 27 is positioned. Key 27 is pivotally secured, by a hollow rivet 28, to drive shaft 21 which is preferably secured to the mid-portion of shaft 21 and radially removed from the axis of shaft 15. The key is positioned so that its central portion 29 is normally parallel to and flush with the outer surface of the drive shaft. The opposite ends of the key are provided with detent portions 30 and 31, which project beyond the surface of the shaft toward the top edges of a pair of stop elements, or lugs, 32 and 33 positioned beneath drive shaft 21. When the key is in its normal position parallel to the surface of shaft 21, as shown in Figure 2, the projecting portions 30 and 31 terminate just short of engagement with the said lugs. The lugs may be formed in any convenient manner but, as more clearly illustrated in Figure 4, preferably comprise upwardly turned portions of the base 34 of housing 24.

Wrapped around shaft 21 is a flexible driving element 35, preferably comprising a string or cord, which has its mid-portion passing through hollow rivet 28, and its ends engaged around pulley 20 and connected to one end of a coil spring 36, the other end of which is anchored to the pulley, as at 37. Spring 36 maintains sufficient tension on cord 35 to assure immediate response of the mechanism to rotation of shaft 21.

It is preferred that the cord pass through the hollow rivet, but in the broader aspect of the invention, other methods of positioning the central portion of the cord may be employed. For convenience in describing the operation of the mechanism, that part of cord 35 which appears to the left of rivet 28, in Figures 2 and 3, is designated by the numeral 35a, while the remaining portion, to the right of the rivet, is designated by the numeral 35b. When the cord is wrapped around the shaft and in contact with key 27, on

both sides of the pivot, the tension of the cord enables it to hold the key in its normal position parallel with the shaft, as seen in Figure 2, thus permitting the shaft to be turned in either direction.

In operation of the device, it should be understood that the apparatus is designed to terminate rotation of shaft 21 after a predetermined number of revolutions, in either direction, from terminal positions lying at opposite ends of the range of rotation. More specifically, in the device, as illustrated, it is intended to limit the rotation of shaft 21 to approximately 3 turns in each direction; three turns being just sufficient to rotate pulley 20, and therefore rotors 13 and 14, through 180°, that is, from one terminal position in which the rotor plates are completely meshed with the stator plates, to another terminal position in which the plates are completely out of mesh.

With particular reference to Figures 1 and 2, wherein the mechanism appears in identical positions of adjustment, let it be assumed that it is desired to change the capacitance of condenser 10. Drive shaft 21 is turned manually—knob 38 being provided for this purpose—either to the right or left, depending upon whether it is desired to increase or decrease the capacitance. If, for example, the drive shaft is rotated in a counter-clockwise direction, from the position shown in Figures 1 and 2 toward the position illustrated in Figure 3, that portion of the cord designated by the numeral 35b, on the right hand side of the pulley is drawn downwardly and wrapped around that portion of shaft 21 which lies to the right of pivot 28, thereby turning pulley 20 and shaft 15 in a clockwise direction to move rotors 13 and 14 out of mesh with the stators 11 and 12, and thus reduce the capacitance of condenser 10. At the same time cord portion 35a, lying to the left of the pivot, is drawn upwardly away from the shaft, and wrapped around the pulley.

As the mechanism approaches the terminal position, and just prior to the last half turn of shaft 21, (the position shown in Figure 5) cord 35a moves out of contact with the left side of key 27, thereby releasing the key for pivotal movement in a counter-clockwise direction. As illustrated in Figure 6, continued rotation of the shaft, for approximately one-quarter turn, brings cord portion 35b in line with extension 31 of the key and, in response to further rotation of the shaft, cord portion 35b engages extension 31 and rotates the right end of the key inwardly to its fully retracted position.

Thus key 27 is pivoted in a counter-clockwise direction to move extension 30 outwardly to extended position and into contact with lug 32, as illustrated in Figures 3 and 4, thereby stopping further rotation of the shaft in this direction. It is understood, of course, that when the shaft reaches this position, pulley 20 has rotated shaft 15 and consequently rotors 13 and 14 of the capacitor to the terminal position wherein they are completely out of mesh with the stator.

It is readily seen that from the terminal position just described, drive shaft 21 may be rotated only in a clockwise direction and that rotation in this direction will remove the last turn of cord portion 35b from contact with the right end of the key, and cord portion 35a will wind upon the shaft to the left of the hollow rivet and into contact with the intermediate edge 29 of the key, at the point indicated in Figure 2 by the numeral 39, thereby returning the key to its normal par-

allel position, wherein extensions 30 and 31 again clear lugs 32 and 33.

Continued rotation of the drive shaft in the clockwise direction serves to unwrap cord portion 35b from the shaft and wraps portion 35a about the left side of said shaft until the last turn of cord portion 35a moves the key into a retracted position which is the reverse of that shown in Figure 3, i. e., a position in which extension 30 is retracted and extension 31 is extended and makes contact with lug 33, to stop further rotation in that direction.

In the device as illustrated and described, it will now be understood that the two terminal positions correspond to positions of the rotor relative to the stator. In one of said terminal positions, the plates are completely out of mesh, and, in the other terminal position, the plates are completely meshed. It is evident, of course, that the selection of these terminal positions is a matter of choice, and that by varying the relative positions and dimensions of the parts of the apparatus, other terminal positions may be selected.

The particular environment in which the invention has been illustrated and described is exemplary of the principles involved, and it is to be understood that the concepts of the invention are applicable to a wide variety of mechanisms in which it is desired to stop the movement of rotating elements after a predetermined number of revolutions.

I claim:

1. Apparatus for controlling the rotation of a rotatable member, comprising, flexible drive means engaged with said member and movable with said member during rotation of the latter, a stationary stop element, and stop means on said member movable with respect to said member between a position in which said stop means engages said stop element and a position in which said stop element and said stop means are disengaged, said flexible drive means being in bearing engagement with said stop means and effective to cause movement of the latter between its said positions in response to predetermined angular displacements of said rotatable member.

2. Apparatus for controlling the rotation of a rotatable shaft, comprising, flexible drive means wrapped about said shaft in driven engagement therewith, a stop element, and stop means pivotally mounted on said shaft for movements with respect to the shaft between a position in which said stop means engages said stop element and a position in which said stop element and said stop means are disengaged, the wrapped portion of said flexible drive means further being in bearing engagement with said stop means and being movable along the shaft, in response to predetermined angular displacements of said shaft, to cause pivotal movement of said stop means between its said positions.

3. Apparatus for controlling the rotation of a rotatable shaft, comprising, a rotary element having its axis of rotation extending transversely with respect to and spaced from the axis of said shaft, a flexible drive cord or the like having its ends secured to said rotary element and an intermediate portion wrapped about said shaft, stop structure, and detent means carried by said shaft and having spaced portions, said detent means being movable between a position in which one of said spaced portions engages said stop structure and a position in which the other of said portions is so engaged, the wrapped portion of said drive cord further being adapted for driving en-

gagement with said detent means, selectively, and being movable along said shaft—in response to rotation of the latter—to establish such selective driving engagement.

4. Apparatus for controlling the rotation of a rotatable shaft, comprising, a rotary element having its axis of rotation extending transversely with respect to and spaced from the axis of said shaft, a flexible drive cord or the like having its ends secured to said rotary element and an intermediate portion wrapped about said shaft, said shaft being provided with a slot extending longitudinally thereof, stop structure, elongated key means disposed within said slot, and means pivotally mounting said key means intermediate its ends, said key means being displaceable about said mounting means to cause selective engagement of the opposite end portions of said key means with said stop structure, the wrapped portion of said drive cord further being in bearing engagement with said key means and being movable along the shaft in response to rotation of the latter, such movement along the shaft being

effective to cause pivotal movements of said key means between its said positions.

5. Control apparatus for a variable capacitor having a control shaft, a pulley secured to said shaft, a counter-shaft radially removed from said control shaft, a drive cord interconnecting said counter-shaft with said pulley, whereby rotation of said counter-shaft turns said pulley to rotate said control shaft, a stationary element, an elongated member pivotally mounted on said counter-shaft and movable by said cord into an extended position in which said member abuts said stationary element.
